Primary Examiner — Susan Moon Lee*(74) Attorney, Agent, or Firm* — Dunlap Bennett & Ludwig PLLC(57) **CLAIM**

The ornamental design for a pet toy, as shown and described.

DESCRIPTION

- FIG. 1 is a top front perspective view of a pet toy;
FIG. 2 is a front elevation view thereof, the rear elevation view being a mirror image thereof;
FIG. 3 is a right elevation view thereof;
FIG. 4 is a left elevation view thereof;
FIG. 5 is a top plan view thereof;
FIG. 6 is a bottom plan view thereof; and,
FIG. 7 is a section view thereof, taken along line 7-7 of FIG. 5.
